Primary Examiner — Elizabeth A. Albert(74) *Attorney, Agent, or Firm* — ScienBiziP, P.C.(57) **CLAIM**

The ornamental design for a bottle opener, as shown and described.

DESCRIPTION

FIG. 1 is a rear perspective view of a bottle opener showing my design;

FIG. 2 is a front perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is another front perspective view thereof.

The broken lines in the drawings are employed to show unclaimed portions of the bottle opener, and form no part of the claimed design.

1 Claim, 9 Drawing Sheets(56)
